ATTORNEY,

UNITED STATES PATENT OFFICE.

WILLIAM J. BALDWIN, OF BROOKLYN, NEW YORK.

STEAM-RADIATOR.

SPECIFICATION forming part of Letters Patent No. 393,287, dated November 20, 1888.

Application filed October 6, 1887. Serial No. 251,600. (No model.)

To all whom it may concern:

Be it known that I, WILLIAM J. BALDWIN, a citizen of the United States, residing at Brooklyn, in the county of Kings and State of 5 New York, have invented new and useful Improvements in Radiators, of which the following is a specification.

This invention relates to an improvement in radiators, as set forth in the following specification and claims, and illustrated in the accompanying drawings, in which—

Figure 1 represents a section along the line xx of a radiator embodying my invention. Fig. 2 is a vertical section along the line yy , Fig. 1. Fig. 3 is a longitudinal section of a modification. Fig. 4 is a transverse section of Fig. 3.

In the drawings, the letter A designates a hollow casing of cast-iron or other suitable 20 material, which casing may have the general shape of a radiator. It is provided with a steam-inlet, a , and a steam-outlet, a' . In the interior of the casing are pockets B, which are preferably formed on the longer sides of the 25 casing. Said pockets may be cast directly on the sides of the casing or subsequently affixed thereto in any manner so that they will be water-tight. These pockets B open upwardly and receive the water of condensation. When 30 steam enters the hollow casing A, the water contained in the pockets B is heated to a temperature corresponding to that of the steam, and when the steam is turned off the water gives off its heat, imparting it to the air exterior to the casing whereby the heat of the water of condensation is utilized and sudden 35 changes of temperature are avoided.

An advantage of having several shallow pockets is that in case the water contained 40 therein should freeze the casing would not be

liable to fracture. Fracture of the casing is also prevented by having each pocket with a gradually - increasing cross - section from its bottom upward.

In Figs. 3 and 4 the casing A is shown in the 45 form of a pipe or tube having a pocket, B, on each side which extends throughout the length of the same. In case such pipes are to be used for heating ships and the like, where they are liable to be vibrated or tilted, partitions b may 50 be made in the pockets B, so as to divide the same into compartments, whereby the water is less liable to flow out of the pockets as the pipes are tilted, or the mouths of the pockets may be partly covered for the same purpose. 55

What I claim is—

1. A radiator - casing having open water-pockets B, arranged one above another upon the sides of the interior of said casing and adapted to collect and retain the water of condensation, substantially as described. 60

2. A radiator-casing having water-pockets B, arranged one above another within said casing, said pockets extending from end to end and being open at the top, substantially 65 as described.

3. A radiator-casing having water-pockets B, arranged one above another within said casing and extending from end to end thereof, said pockets being provided with transverse 70 partitions b at intervals and open at their tops, substantially as described.

In testimony whereof I have hereunto set my hand and seal in the presence of two subscribing witnesses.

WILLIAM J. BALDWIN. [L. S.]
